CONTROL FOR GYRATOR-TYPE WASHING MACHINES

Lee B. Green, Lakewood, Ohio, assignor to The Borden Company, Warren, Ohio, a corporation of Ohio

Application July 26, 1932, Serial No. 624,782

3 Claims. (Cl. 259—101)

My invention relates to agitator-driving mechanisms for washing machines of the type in which an agitator (or socalled gyrator) oscillates about a vertical axis within a tub in which the clothes are immersed in the cleansing liquid. Generally speaking, the objects of my invention are those of effectively preventing certain serious objections commonly encountered because of the relatively small height at which the bottom of the agitator is spaced upwardly from the bottom of the tub, namely the jamming of parts of clothes or other washable goods between the agitator bottom and the tub bottom, the wasteful accumulation of soap chips or the like under the agitator, and the dirt-streaking of the portions of the goods which ordinarily are forced under the agitator during the inserting of the goods.

With a washing machine of this class, it has heretofore been customary to introduce both the soap chips (or other solid detergent material) and the washable goods into the water in the tub while the agitator is halted. With the water thus in a quiescent state, a considerable portion of the soap chips will descend in the water and collect on the bottom of the tub. Then when the goods are pressed down into the water, portions of the goods (such as sleeves and collars of garments, corners or ends of towels, and even entire handkerchiefs) usually are forced into the clearance space between the bottom of the tub and the bottom of the agitator.

While the subsequent oscillating of the agitator causes a violent agitation of the water and goods radially outward of the agitator, this agitation is relatively slight within the said clearance space, and the soap under the agitator tends to gum adjacent portions of the goods to the tub bottom, so that these portions cannot move freely. As the result, such portions are often torn, and even if not torn are rubbed back and forth over undissolved soap and over particles of dirt adhering to the soap.

Then when the agitator is halted at the end of the washing operation, so that the water again becomes quiescent, more of the loosened dirt settles down on the tub bottom; and when the goods are being drawn out of the tub, the portions which were under the agitator are dragged over the accumulated sediment and come out with streaks of dirt and the like which must be scrubbed off manually. And, since the accumulation of such sediment increases when successive batches of goods are washed without an intervening entire emptying and rinsing of the tub, the just recited soiling and streaking of the goods becomes all the more objectionable. Moreover, the portions of the goods which are under the agitator during the washing operation are squeezed so tightly that the wash water cannot swish back and forth through these parts of the

goods; consequently, such portions of the goods—even if not objectionably streaked—are not adequately cleansed, so that further manual labor is required to complete the washing.

What is more, considerable lint usually collects also with the dirt and other sediment in the bottom of the tub and enhances the streaking of the goods; and a mixture of lint, soap and sediment is apt to be drawn into the lower bearing of the agitator so as to gum this bearing and increase the torque required for restarting the machine.

My present invention aims to overcome all of these objections without in any way complicating the actuating mechanism or appreciably increasing the manufacturing cost, and without requiring special skill or attention on the part of the user. More particularly, my invention aims to provide means for the above mentioned advantageous purposes which can readily be applied to washing machines of the recited type when the agitator-oscillating mechanism includes a pitman connected at one end to a crank-pin or eccentric, and also includes means for varying the distance between the axis of the crank-pin or eccentric and the shaft carrying either of the latter.

Illustrative of the manner in which my invention may be applied to several different types of washing machines provided with an adjustable control for the arc of oscillation of the gyrator,

Fig. 1 is a central and vertical section through a portion of a washing machine in which the stroke-controlling mechanism includes an upright and vertically movable worm member spirally allied through a stroke-adjusting eccentric, showing this worm in the lowermost position in which it adjusts the mechanism for the minimum agitator stroke.

Fig. 2 is an enlargement of a portion of Fig. 1, with the worm member halted (by direct engagement with another part) in the extreme raised position in which it has reduced the stroke of the agitator to a minimum suitable for securing the objects of my invention.

Fig. 3 is a plan view of the gearing and the lower half of the gear casing, taken when the worm member is in its maximum-stroke effecting position of Fig. 1.

Fig. 4 is a view corresponding to portions of Fig. 3, taken when the worm member is in its minimum-stroke effecting position of Fig. 2, and with the portion 4A somewhat enlarged to clarify the drawings.

Fig. 5 is a section, allied to Fig. 1, through a portion of a washing machine in which the stroke-controlling worm member is adjusted by means of a lever and link arrangement, showing this member in its lowermost or maximum-stroke effecting position.

Fig. 6 is an enlargement of a portion of Fig. 5,

showing the said worm member as halted (in its minimum-stroke effecting position) by the engagement of a forked link with a stationary stop.

Fig. 7 is an enlarged plan section taken along the line 7—7 of Fig. 5.

Fig. 8 is a perspective view showing my control arrangement as used in connection with a mechanism in which an oscillation-effecting pitman is varied in its stroke by adjusting a swinging sector upon which the crank-pin for the pitman is mounted, showing this sector in a position affording a maximum stroke.

Fig. 9 is a plan view of the parts shown in Fig. 8, and Fig. 10 is a similar plan view showing the sector as halted in the position affording the minimum stroke.

Fig. 11 is a perspective view of parts of an agitator-oscillating mechanism allied to Fig. 8, but in which the crank-pin is mounted on a slide, showing this slide in a position affording a maximum stroke.

Fig. 12 is a plan view of the parts shown in Fig. 11, with dotted lines showing the positions of the slide and the crank-pin in the halted position affording the minimum stroke.

In experimenting with washing machines of the upright tub and oscillating agitator type in which the stroke or arc of oscillation can be adjusted without halting the agitator, I have made the following observations and discoveries, on which my present invention is based:

(A) With the agitator or gyror of such a washing machine oscillating about a vertical axis, the centrifugal action of the agitator on the water in the tub is still sufficient to prevent undissolved soap chips as well as parts of the washable goods from entering the space under the agitator when the stroke of the agitator is reduced to a minor fraction of its maximum, as for example to from one-tenth to one-twelfth of the maximum stroke.

(B) When the stroke is adjusted to such a small fraction of its maximum, the impeller blades of the agitator swing through so short an arc, and move in each direction at so slow a rate, as not to interfere with the convenient and safe inserting or removal of the goods which are being washed.

(C) The operation of the agitator at such a small fraction of its maximum stroke effectively prevents portions of the goods from being forced between the agitator and the bottom of the tub and entirely eliminates the heretofore encountered streaking of goods with dirt.

(D) The continuous operation of the agitator at a stroke not less than such a small minimum of its maximum stroke entirely avoids the gumming of the agitator by soap chips and lint; and likewise keeps soap chips, lint and the like away from the bottom bearing for the agitator.

(E) The proportion of the needed minimum stroke to the maximum stroke can readily be determined by the washing machine manufacturer, according to the speed of oscillation and length of stroke of the agitator, the height of the clearance space between the tub bottom and the agitator, and the diameter of the agitator with respect to the tub.

(F) No dependence should be placed on the judgment of the user of a washing machine for making the adjustment down to the needed minimum stroke if the machine is of the type in which such adjustment can be made without halting the oscillation of the agitator, because the user is not limited as to the permissible ex-

tent of the stroke reduction) is apt to reduce this to such an extent as not to secure the objects of my invention. Hence an avoiding of the heretofore objections and difficulties in the use of washing machines equipped with means for manually controlling the stroke of the agitator can only be secured by positively limiting the minimum stroke to which this adjustment can be made.

In harmony with these observations, I have also found that the needed halting of the stroke adjustment (in the direction in which it reduces the stroke of the agitator) can be accomplished both easily and cheaply with varying types of agitator-oscillating mechanisms, and particularly so when such a mechanism includes a pitman actuated by an eccentric or crank-arm which is adjustable as to its throw.

For example, Figs. 1 to 4 show portions of a washing machine allied to my Patent #1,735,459, in which an agitator 1 (Fig. 1) is supported by an upright shaft 5 within a tube 2 with lower portions 2A of the agitator spaced by a quite short distance from the bottom 1A of the tub. Fastened to the agitator shaft 5 below the tub is a pinion 6 meshing with a sectoral gear 7 (Fig. 3) which has a pin 8 rising from the gear intermediate of the teeth of the gear and an upright shaft on which the gear swings, the sectoral gear 7 being of considerably greater radius than the pinion 6 so as to amplify oscillations imparted to the sectoral gear by an eccentric rod 9 connected at one end to the riser pin 8. Sleeved by an eccentric strap 10 at the other end of the eccentric rod is an eccentric 11 supported by a worm wheel 12 which meshes with a worm 13 on the horizontal shaft 14 of an electric motor 15. To permit an adjustment of the eccentricity or throw of the eccentric 11 with respect to the stationary upright axis of the worm wheel, the worm wheel has an integral riser projection in the form of a crescent 16 freely spaced from the eccentric strap, which projection is housed by and rotatable with internal gear 17 formed on eccentric, the axis 18 of the internal gear being spaced from the axis 19 of the eccentric.

Within the smooth shorter wall of the crescent 16 and meshing with the internal gear 17 is a pinion 20 which is coaxial with the worm wheel 12 and which has a downwardly extended hub 20A journaled in a counterbore 21 of the worm wheel. Thus arranged, a rotation of the pinion 20 will rotate the eccentric 11 about the crescent 16 so as to vary the distance between the axis 19 of the eccentric and the common axis 22 of the said pinion and worm wheel.

To rotate the pinion for this adjusting purpose, I make the pinion 20 hollow and provide it with an internal spiral thread 23 fitting an upright worm 24 which extends slidably through the pinion. This worm shaft is fastened at its lower end to an upright rack 25 which meshes with a manually rotatable gear 26, the rack having a flat bearing against a guide 27 to cooperate with the gear in preventing rotation of the rack and hence of the worm shaft 24. Thus arranged, the upright rack 25 and the worm shaft 24 constitute a vertically movable worm member, the upper portion of which is spirally splined to the pinion so that vertical movements of this member will rotate the pinion 20 and hence will also rotate the eccentric 11 about the crescent 16, the longer arcuate surface of which crescent constitutes an inner or auxiliary eccentric for adjusting the throw of the main eccentric 11.

As here shown, the guide 27 is formed on the interior of a stationary tubular riser 28 in which the depending tubular hub 29 of the worm wheel 12 is journaled, and the lower end portion of this hub is counterbored to present a downwardly facing annular shoulder 30. This shoulder is at such a height that it will be engaged (as in Fig. 2) by the upper end of the rack 25 when the rack has been raised until the upright worm 24 fastened to this rack has rotated the inner or throw-adjusting eccentric 11 for somewhat less than a half-turn from the position of that eccentric when the rack and the upright worm were in their lowermost positions as shown in Fig. 1.

With the mechanism thus arranged, the combined rack and upright worm member hold the throw-adjusting inner eccentric 11 in the position shown in Fig. 3 when the said member is in its lowermost position of Fig. 1, namely a position in which a common plane P through the axis 19 of the inner eccentric and the axis 22 of the pinion 20 (and hence likewise of the driving worm wheel 12) extends also through the axis 8A of the crank-pin 8 on the sectoral gear 7. In this position the main eccentric has its maximum throw, and the oscillation of the sectoral gear by the pitman 9 is amplified by the pinion 6 so that the agitator oscillates through a correspondingly enlarged arc A.

When the rack member is raised, by rotating the control pinion 26, the throw of the main eccentric is decreased, but this decrease cannot reach the zero point because the rack is halted by the annular stop shoulder 30 before the inner or adjusting eccentric has been rotated a full half turn from its position in Fig. 1, namely when the medial plane through the axes 19 of the internal gear 17 and the axis 19 of the worm wheel 12 is at an acute angle B to the medial axis of the pitman 9, which angle faces the pivot pin 9 of the sectoral gear. Consequently, the minimum throw permitted by the adjustment will still cause the sectoral gear 7 to oscillate between the extremes shown in dotted lines in Fig. 4, so that the agitator will oscillate through the arc C of that figure instead of being halted.

Moreover, with the motor 15 running at a substantially constant speed, the time required for the agitator to move through the minimum arc C of Fig. 4 will still be the same as that needed for the maximum arc A of Fig. 3; so that the speed at which the impeller blade moves with the minimum adjustment of Fig. 4 is quite low, thereby making it perfectly safe for the user of the machine to remove and replace goods while the agitator has its positively defined minimum stroke.

The minimum oscillation thus permitted by my mechanism can readily be varied by varying the height at which the stop shoulder 30 is disposed, according to the number of vanes on the agitator, the rate at which the motor oscillates the agitator, and the diameter of the agitator, since the manufacturer of the washing machine can easily determine experimentally what minimum arc of oscillation will be needed to assure a continuous outward forcing of water from under the agitator. For example, with the general type of washing machine here illustrated, this arc may be from one-twelfth to one-eighth of the maximum oscillation for which the machine is adjustable, namely so small an arc as not to interfere with the ready inserting and withdrawing of the goods which are being washed, the size of the arcs C and B in Figs. 4 and 4A having been ex-

aggerated to make the positions of parts of the mechanism more clearly apparent.

In practice, my provision for limiting the minimum arc of agitator oscillation for which the machine can be adjusted introduces no difficulties for the user, who merely is instructed to start the machine by closing a switch S in the circuit leading to the motor, to adjust the agitator stroke until halted at its minimum before inserting or withdrawing any clothes, and to open the switch only after all goods have been removed from the tub. Since the driving motor still rotates continuously (although substantially idle) while the goods in the tub are being removed and replaced, and since the initial batch of goods can also be inserted while the motor is running, the motor is not required to start under the torque required for starting it from rest under considerable torque, so that the motor can also be of somewhat lower power than that required with the heretofore employed mechanisms.

However, while I have heretofore described my control arrangement in connection with a mechanism in which a stop engages a part fast upon a worm which rotates a throw-adjusting secondary eccentric, the halting of the adjustment in the position in which it affords a relatively short but still effective oscillation of the agitator may be effected by a stop positioned for engaging some other one of the elements which are moved during the adjusting of the said throw.

For example, Figs. 5 to 7 show my control arrangement as applied to the washing machine driving mechanism disclosed in my United States Patent #1,844,503, which mechanism also includes a main eccentric 17 swiveled upon an inner eccentric, the latter being rotationally adjustable by vertically moving an upright worm 24 and operatively connected as in my previously described figures.

In this case, the vertical movement of the upright worm is effected by a forked link 46 connecting the said worm with a lever 47, and this link is halted in its upward (or throw-decreasing movement) by engagement with a stop finger 48 on a stationary part 49 of the machine, as shown in Fig. 6, instead of having the halting effected (as in Fig. 2) by engagement with an also moving part of the agitator-driving mechanism.

Since an eccentric provided with means for adjusting its throw is operatively a crank of adjustable arm length, my invention also lends itself readily for use with washing machine mechanisms in which the actuated end of the pitman is connected to a crank pin which can be adjusted as to the distance between the axis of that pin and the axis of the shaft of the crank, as for example with either of the two crank-arm-adjusting arrangements shown in my United States Patent #1,796,753.

For example, Figs. 8, 9 and 10 show a mechanism in which a crank pin 30 is fastened to a crank-arm 31 which is pivoted to a worm wheel 32 on a screw 33 extending parallel to the axis 65 34 of the worm wheel. Underhanging the crank-arm and adapted to be rotated by a member 35 which is journaled in the hub 36 of the worm wheel is a gear 37 which meshes with a segmental rack 38 fastened to the crank-arm 31. In this case, the free end of the crank-arm slides in a guide 39 fastened to the worm wheel, and the crank-arm has a projecting finger 40 disposed for engaging one end of this guide to limit the swinging of the crank-arm in the direction in which

the axis of the crank pin 30 approaches the axis 34 of the worm wheel.

In Figs. 11 and 12, the crank pin 30 is fast upon a plate 44 which slides (in a general plane at right angles to the axis of the worm wheel 32) between two guides 41, and one end of this sliding plate has two fingers 42 adapted to simultaneously engage the corresponding ends of both guides to limit the movement of the sliding plate 10 in the direction in which the axis of the crank pin approaches the axis 34 of the worm wheel.

With the embodiments of Figs. 9 to 12 inclusive, the position of the stop fingers with respect to the crank pin can readily be so determined 15 that the engagement of each stop finger with a guide end will occur when the spacing between the crank pin and the axis of the worm wheel is such as to effect a minimum throw of the pitman (corresponding to that of eccentric rod in Fig. 20 4A) to insure a continuous agitator of the water and the immersed goods radially outward of the agitator, so as to accomplish the objects of my invention.

It will also be obvious that in the arrangement 25 of Figs. 9 to 12 the guides which engage the stop-fingers are fast on a worm wheel which continually rotates during the operation of the machine, whereas the halting is effected by engagement with a stationary element in the embodiments 30 of Figs. 1 and 5. Hence I do not wish to be limited as to the nature or movability of the element which effects the halting, this being immaterial so long as the member which is halted is one of the elements which are moved 35 during the adjustment of the arc of oscillation of the agitator; and so long as this halting occurs when the said arc of oscillation suffices to effect a continuous agitation of the water and goods radially outward of the agitator, thereby overcoming all four of the heretofore objections (enumerated in numbered paragraphs in the earlier part of this specification), which objections are encountered whenever the mechanism is such that the arc of oscillation 40 can be reduced to zero while the driving shaft of the machine is rotating.

Nor do I wish to be limited to the general types 50 of washing machine mechanisms here illustrated, since the nature of the adjustable stroke mechanism interposed between the continuously rotating driving shaft of the machine and the oscillatable agitator is immaterial, so long as means are provided for positively limiting the minimum arc of oscillation of the agitator to 55 the above recited still effective stroke.

However, the disposition of the stop with respect to the part halted by this stop is preferably such as to reduce the stroke of the agitator to a quite small fraction of the maximum stroke, so as to allow ample room for inserting and removing goods in the tub and also to slow up the movement of the impellers of the agitator sufficiently to avoid any interference with the handling of the goods and any forcible impact 60 of the impellers on the hands of the user.

I claim as my invention:

1. In a washing machine, an upright tub, an agitator oscillatable about a vertical axis within the tub, a continuously rotating member; instrumentalities operatively connecting the agitator with the rotating member whereby the rotation of that member oscillates the agitator, an adjusting mechanism whereby the stroke of the agitator effected by the said instrumentalities

can be varied without halting the rotating member, the said mechanism comprising a plurality of movable elements, and a stop element in the path of movement of a certain one of the said movable elements of the adjusting mechanism, 5 the stop element being positioned for engagement by the said certain one of the movable elements for positively preventing the actuation of the adjusting mechanism in the stroke-reducing direction beyond a point where the oscillation of 10 the agitator is only slightly greater than the minimum required for continually urging water within the tub radially outward along the bottom of the tub from under the agitator; and a stationary casing supporting the said movable 15 elements, the said stop element being fast with respect to the casing and the said one of the movable elements being movable respectively toward and away from the said stop element by relatively opposite actuations of the adjusting 20 mechanism.

2. In a washing machine, an upright tub, an agitator oscillatable about a vertical axis within the tub, a continuously rotating member; instrumentalities operatively connecting the agitator with the rotating member whereby the rotation of that member oscillates the agitator, 25 an adjusting mechanism whereby the stroke of the agitator effected by the said instrumentalities can be varied without halting the rotating 30 member, the said mechanism comprising a plurality of movable elements, and a stop element in the path of a certain one of the said movable elements of the adjusting mechanism, the stop being non-adjustably positioned for engagement 35 by the said certain one of the movable elements so that the interengagement of the last named two elements positively prevents the actuation of the adjusting mechanism in the stroke-reducing direction beyond a point where the oscillation of 40 the agitator is only slightly greater than the minimum required for continually urging water within the tub radially outward along the bottom of the tub from under the agitator.

3. In a washing machine, an upright tub, an agitator oscillatable about a vertical axis within the tub, a continuously rotating member, instrumentalities operatively connecting the agitator with the rotating member whereby the rotation of that member oscillates the agitator, 45 an adjusting mechanism whereby the stroke of the agitator effected by the said instrumentalities can be varied without halting the rotating member, the said mechanism comprising a plurality of movable elements, and a stop element in the path of a certain one of the said movable elements of the adjusting mechanism, the stop element being non-adjustably positioned for engagement 50 by the said certain one element so that the interengagement of the last named two elements prevents the actuation of the adjusting mechanism in the stroke-reducing direction beyond a point at which the arc of oscillation is approximately not less than one-tenth nor more 55 than one-twelfth the maximum arc of oscillation for which the agitator can be adjusted by the said mechanism; and a casing normally completely housing the said stop element and the said certain one element to prevent access to the 60 said interengaging elements by the user of the washing machine.

LEE B. GREEN.
